UNITED STATES PATENT OFFICE.

WILLIAM C. GARWOOD, OF DAYTON, OHIO.

PHOTOGRAPHER'S PRINTING AND RETOUCHING CABINET.

Application filed August 1, 1921. Serial No. 429,086.

To all whom it may concern:

Be it known that I, WILLIAM C. GARWOOD, a citizen of the United States, residing at Dayton, in the county of Montgomery and 5 State of Ohio, have invented certain new and useful Improvements in Photographers' Printing and Retouching Cabinets, of which the following is a specification.

This invention relates to photographers' 10 printing and retouching cabinets and relates mainly to the printing means enabling photographers, after retouching negatives, to make contact prints therefrom.

The object of the invention is to produce 15 a compact cabinet having certain foldable or collapsible parts which will materially reduce the size of the cabinet when the same is not in use but which may be readily set up in their useful positions either for re- 20 touching or printing.

A further object of the invention is to provide in conjunction with the cabinet a novel arrangement of illuminating means 25 adaptable both for retouching and printing purposes; also a novel arrangement of switches whereby the several electric lamps may be individually or collectively controlled and automatically extinguished or 30 cut out when the printing platen is lifted after a print has been made, thereby saving current.

The cabinet also comprises means adding 35 greatly to the convenience and work of the operator by enabling him to dispose of his work and the tools or implements used in connection therewith with the greatest convenience.

With the above and other objects in view, 40 the invention consists in the novel construction, combination and arrangement herein fully described, shown and claimed.

In the accompanying drawings,

Fig. 1 is a front elevation of the cabinet with the movable parts thereof folded;

Fig. 2 is a rear elevation of the cabinet 45 showing the parts thereof in position for the retouching operation;

Fig. 3 is a side elevation of the same;

Fig. 4 is a plan view of the cabinet with 50 the parts arranged as in Fig. 1 but omitting the printing platen and the parts immediately associated therewith;

Fig. 5 is a similar view showing the printing platen in position;

Fig. 6 is a vertical section through the

negative holding frame and printing platen on the line 6—6 of Fig. 5;

Fig. 7 is a fragmentary, vertical section showing the platen holding latch and the common switch controlling the illuminating 60 means;

Fig. 8 is a fragmentary, vertical section showing the work holding means.

Figure 9 is a wiring diagram of the electrical equipment of my device. 65

The cabinet contemplated in this invention is shown conveniently as comprising four legs 10 which are connected by suitable horizontal members 11 and 12, adjacent to the top thereof to provide an upper illuminating compartment 13 which is lined on all four sides with sheet metal protecting walls 14 and a similar bottom wall 15, having attached thereto sockets 16 and 17 for electric lamps 18 and 19, the lamp 20 70 which fits into the socket 17 being arranged centrally as shown in Fig. 4, and the lamps 18 and 19 extending inwardly from the four side walls of the compartment as shown in Fig. 4. In addition to the lamps above referred to, I may employ additional corner lamps 21 supported by sockets 22 attached to the corner legs 10. A small pilot lamp 23 is also arranged in the compartment 13 and is of a non-actinic color, the same being 80 used while positioning the negative and sensitized paper preparatory to making a print. 85

At the front of the cabinet there is arranged a switchboard 24 having a series of switches 25 for individually controlling the illuminating lamps hereinabove referred to. Said lamps are also controlled by a common switch hereinafter described. Corner brackets 26 of metal are used to fasten the frame members of the stand securely together. The stand is mounted upon castors or rollers 27 and in conjunction with one or more of the legs, preferably two of the legs, I use floor stops 28 adapted to be depressed by the foot of the operator so as to frictionally engage the floor and prevent the stand from moving on its castors or rollers, this being important in a cabinet of the class referred to. The floor stops 28 are of such construction that their braking action may 100 be released by foot pressure applied thereto.

As shown, the rear side of the compartment 13 is left open for ventilation purposes and the rear wall lamp 19 is supported by means of a bracket plate 29 of 110

channel formation extending vertically between upper and lower horizontal members 11 and 12 of the stand.

Connected to the top of the stand by means of hinges 30 is a negative supporting or holding frame 31 which is adapted to be tilted to any desired angle as indicated by dotted lines in Fig. 3. The frame 31 carries oppositely extending spring pressed bolts 32 adjacent to the upper free corners thereof, which are adapted to engage arcuate series of holes 33 in side shields 34 of quadrantal shape and connected to the top of the stand by means of hinges 35, adapting said shields 34 to be extended vertically upward, as shown in Figs. 2 and 3, or folded downwardly on opposite sides of the stand to pendent positions, as shown in Figs. 1 and 4. The side shields 34 are also adapted to be supported in horizontal position, as indicated in Fig. 2, by means of props or braces 36 pivotally connected to the legs of the stand at 37 and engaging notches 38 in the under sides of the shields 34. The shields thus form hinged table legs for supporting various articles used by the retoucher. Each of the props or braces 36 is connected to the stand when in an upright position by means of a hook 39 engaging a pin 40 on the stand.

Illuminating lamps 41 are arranged under the frame 31 and supported in relation thereto and at a predetermined and constant distance therefrom by means of brackets 42, as shown in Fig. 3. The lamps 41 are furthermore arranged in such manner that when the frame 31 is lowered to its horizontal position on the stand, they will lie between the lamps 18, 19 and 21, hereinabove described as shown in Fig. 4 and in the same horizontal plane.

A flexible, opaque curtain 43 is fastened along its lower edge to the cabinet by means of a clamping bar 44 and extends upwardly along the curved edges of the side shields 34 by which it is supported and is attached near its forward free edge to the corresponding edges of the shields 34 by means of buttons 45 or equivalent fastening means. The flexible curtain 43 is adapted to be folded downwardly at the rear of the cabinet while the side shields 34 are adapted to be folded downwardly on opposite sides of the stand as shown in Figs. 1 and 4, thus placing the entire cabinet in compact formation for storage and transportation.

At the front of the cabinet and adjacent to the top thereof there is arranged a receptacle 46 for art brushes, pencils and other implements used by the photographer, said receptacle being in the form of a V-shaped trough pivotally mounted at 47 so as to swing inwardly and outwardly so as to expose or conceal the contents. Any suitable means may be employed for fastening

said receptacle in its closed position. Immediately adjacent to the top of the stand and extending along opposite sides thereof are grooved guides 48 into which may be removably slid a light diffusing glass or panel 49 and interchangeable mats 50, having openings of different sizes to expose and cover the different portions of a negative while being retouched or printed. The said panel and mats may be inserted through the front of the cabinet and withdrawn in the same direction. Retaining buttons 51 or equivalent means may be used for preventing the parts 49 and 50 from sliding out of place in moving or tilting the stand.

In order to make prints from negatives, I employ a printing platen 52 (see Figs. 5 and 6) which is connected by hinges 53 to an attaching member 54 secured by bolts 55 and thumb nuts 56 to the rear part of the frame. This enables the printing platen to be detached when the cabinet is used for retouching. Extending in a fore and aft direction above the platen 52 is a handle bar 57 having a forwardly projecting handle 58. Interposed between the handle bar 57 and the platen 52 are several sets of springs, each set comprising an upper, longer spring 59 and an underlying lower spring 60, said springs bearing against the platen 52 at several different places, as shown in Fig. 6. The platen 52 is preferably composed of an upper portion or back 61 of plywood and an underlying section or cushion 62 of sponge rubber or equivalent material to enable perfect contact to be obtained between the negative and the sensitized paper, both of which are placed between the platen and a glass panel 63 rabbed into the frame 31 above referred to.

Connected to the under side of the handle 58 by means of a pivot 64 is an L-shaped latch 65, the point 66 of which is adapted to snap under the frame 31, as shown in Fig. 7. This holds the platen 52 firmly against the negative and sensitized paper. In the downward movement of the platen 52 the illuminating lamps are controlled and thrown into operation by means of a suitable common switch, shown for convenience, in Figures 7 and 9, as embodying a pair of spaced contacts 67 and a movable contact 68 shown in the form of a plunger pin held normally elevated and out of electrical contact by means of a spring 69, said pin 68 passing through the frame 31 and being in the path of the handle 58 so that when the handle 58 is pressed downwardly, the circuit is closed and the illuminating lamps energized. Conversely, when the latch 65 is released and the handle 58 lifted, the lamp circuit is broken.

In order to hold the paper and negative against movement while depressing the platen and again on lifting the same, I

employ one or more work holding pins 70 which are adapted to be pressed downwardly below the bottom of the platen by means of one or more springs 71, the latter permitting the pin or pins to yield upwardly when the platen is fully depressed, as shown in Fig. 8.

In Figure 9, the source of supply is indicated by the plus and minus signs. When 10 the switch 68 is closed the pilot light 23 is also lit. There is also a switch 25 to light each of the lamps 18, 19, 20, 21, and 41.

It will be apparent that the photographer's cabinet hereinabove described is 15 susceptible of various modifications and changes which may accordingly be made without departing from the principle or sacrificing any of the advantages of the invention.

20 By means of the switches arranged at the front of the cabinet the illuminating lamps may be turned on and off according to the requirements of any particular negative while making a print therefrom, and the 25 stronger or more opaque portions of the

negative may be more highly illuminated than the weaker portions thereof, this enables a better result in printing to be obtained.

I claim:

1. In a photographer's cabinet, a stand, a negative supporting frame, side light shields hinged to the stand and foldable downwardly to a pendent position beside the stand, means for holding said shields 30 35 either horizontally or in upright position, and illuminating means under said frame.

2. In a photographer's cabinet, a stand, a negative supporting frame having linkage therewith, illuminating means under said frame including a plurality of electric lamps, an individual switch for each lamp, a printing platen connected with said frame, and a common switch controlled by said platen to cut out the lamps when the platen 40 45 is lifted.

In testimony whereof I have affixed my signature.

WILLIAM C. GARWOOD.
